UNITED STATES PATENT OFFICE.

CLARK S. COMSTOCK, SR., OF EAST ORANGE, NEW JERSEY.

GARMENT LOOP OR BUCKLE.

1,250,284.

Specification of Letters Patent.

Patented Dec. 18, 1917.

Application filed February 26, 1913. Serial No. 750,799.

To all whom it may concern:

Be it known that I, CLARK S. COMSTOCK, Sr., a citizen of the United States, residing in East Orange, in the county of Essex and 5 State of New Jersey, have invented certain new and useful Improvements in Garment Loops or Buckles, of which the following is a specification.

This invention relates to certain new and 10 useful improvements in garment loops which are particularly designed for use in connection with buckles for use on overall straps, suspenders or the like, although the invention may be used as a loop member separate 15 from the buckle or in connection with other devices. In devices of this character a loop is provided which is constructed of sheet metal or wire which is designed to engage a button on overalls or trousers. Such loops 20 are usually constructed with a button recess at the bottom and a slightly contracted throat through which the button shank passes when the loop is adjusted in place. The loops are necessarily made of comparatively 25 stiff and heavy metal in order to withstand the strains of use, and sometimes possesses a slight springiness at the throat sufficient to expand slightly when the button shank is passed through the throat. 30 Such loops have not been, however, capable of receiving button shanks of different diameters, since the structures have not possessed sufficient springiness to accommodate larger and smaller button shanks and at the 35 same time to contract to prevent disengagement of the parts after the button is introduced.

According to the present invention I provide a loop which is of sufficiently heavy and 40 stiff construction to withstand all of the strains of use, and which nevertheless has sufficient springiness or yielding qualities at the throat to accommodate a variety of sizes of button shanks. At the same time I 45 am able to retain the general form of loop which has proved satisfactory in service and to produce a construction which is neat and pleasing in appearance and economical in manufacture.

50 Referring to the drawings which illustrate one form of the invention,—

Figure 1 is an elevation of the invention as applied to an overall buckle.

55 Fig. 2 is a view similar to Fig. 1, showing the throat expanded.

Fig. 3 is an edge view.

Fig. 4 is a section on the line 4—4 in Fig. 1.

Referring to the drawings, A indicates the loop portion which in the construction shown is combined with a buckle B, the ends of the wire forming the loop portion being passed through eyes C C formed in the buckle frame and being pointed to form buckle prongs D D. The buckle frame hence forms a support for the loop in the embodiment shown, but it is obvious that the ends of the loop wire may be connected or supported in any other suitable way so that the loop may be used either alone or in connection with other devices.

The loop A to which the invention relates is preferably formed of a single piece of wire so constructed as to provide a throat E and a button recess F. The throat E is preferably contracted with relation to the recess so that a button shank in passing through the throat enlarges the same slightly and then contracts after the shank of the button has reached the recess F so as to prevent accidental disengagement of the button and loop. In the usual construction of loop the sides a a are continued downwardly from the top of the loop directly to the portions b b forming the throat. But in such constructions the rigidity of the material has permitted only a very slight expansion of the width of the throat sufficient to permit the exact diameter of button shank for which it is designed to pass through it with a slight effort.

Such constructions have, however, not permitted the use of buttons having larger shanks since the metal is not sufficiently yielding to permit the introduction of the shank through the throat, nor have they been capable of satisfactory use in connection with buttons of smaller shank for the reason that the throat is then too large to prevent the accidental disengagement of the button. By the present invention the loop is so constructed as to adequately hold the smaller sizes of shank and yet is capable of expanding to receive the larger sizes. This capability is provided in the construction shown by bending the wire to form convolutions c c one on each side of the buckle, the wire forming the convolutions lying in the same plane, or in other words not crossing itself. In the construction shown the convolutions c are arranged

outside of the throat portion E so that the latter presents an unbroken and continuous surface from its top to the recess F. It is preferable to arrange the convolutions *c* as 5 thus described although they may be arranged on the interior of the buckle if desired. In any event it is preferable to arrange the parts in such manner that the convolutions are elongated and narrow so that 10 the several portions of the wire on each side are closely arranged as best indicated in Fig. 4, as thereby the total width of the loop at the throat portion is not unduly extended. Preferably also the wire forming 15 the loop corresponds in its curvature to the curvature of the portions forming the throat, being bent inwardly along the throat as shown. As thus constructed the loop is symmetrical and pleasing in appearance and 20 is not unwieldy or awkward to handle.

Figs. 1 and 2 illustrate the action of the loop. In these figures the latter is shown of normal size and is capable of adequately retaining a button whose shank is slightly 25 larger in diameter than the width of the throat. At the same time the loop is capable of expanding to receive a button whose shank is as large as that indicated in dotted lines in Fig. 1 and in section in Fig. 2. 30 These two sizes of shank represent the usual extremes in buttons of this kind, but if a still larger capacity is required the convolutions of the loop may be separated to a greater extent and larger sizes accommodated. 35

While I have shown and described one form of the invention, it is understood that I do not wish to be limited thereto as various changes may be made therein without 40 departing from the invention. It is possible for instance to form more than one convolution *c* on each side or to vary the shape of the convolutions or their position with relation to the body of the loop. It is preferable 45 that the wire should be continuous from the throat to the button recess so as to avoid interruptions, in order to properly and smoothly guide the shank to the recess. While the loop is chiefly designed for sus- 50 penders or overall loops, it is useful in other connections, as for instance in stocking supporters wherein the elasticity of the loop is of value in accommodating the latter to differences in effective diameters of the but- 55 tons or studs and to differences in thickness of the stockings.

What I claim is:—

1. A garment loop having a throat portion and a button recess of larger diameter than the throat portion, said recess and 60 throat portion being continuously connected and said loop having convolutions at its sides to increase the capacity of the throat portion, said convolutions extending below the narrowest part of said throat portion, 65 and the parts thereof lying in the same plane.

2. A garment loop constructed of a continuous piece of wire or the like, and having a throat portion and a button-receiving 70 recess of larger diameter than the throat portion, and said loop having convolutions on each side of the throat portions, the wire forming the convolutions being uncrossed and extending below the narrowest part of 75 the latter.

3. A garment loop having a throat portion and a button-receiving recess of larger diameter than the throat portion constructed 80 of a single piece of wire, and said loop having a convolution *c* on each side of the throat portion, and formed of uncrossed wire, such convolutions lying throughout in the same general plane as the throat portion and conforming to the latter in shape. 85

4. A garment loop comprising a single piece of wire having a throat portion E and a button recess F, said wire being extended upwardly on both sides of the recess to form a throat and then downwardly along the 90 throat and thence upwardly to form loops *c c*, said loops lying in the same general plane as the throat.

5. A garment loop comprising a single piece of wire having a throat portion and 95 a button receiving recess, the button receiving recess being of larger diameter than the throat portion, said wire being extended upwardly on both sides of the recess to form the throat and thence downwardly along the throat to a point below the latter and thence upwardly along the downward portions to form extended loops, the members of said loops lying in approximately parallel relation. 100

In witness whereof, I have hereunto signed my name in the presence of two subscribing witnesses.

CLARK S. COMSTOCK, SENIOR.
